DESIGN FOR A TELEPHONE JACK BRACKET

Leslie B. Haigh, West Orange, and Franklin A. Stearn, Westfield, N. J., assignors to Federal Telephone and Radio Corporation, New York, N. Y., a corporation of Delaware

Application March 17, 1945, Serial No. 118,530

Term of patent 14 years

(Cl. D26—13)

To all whom it may concern:

Be it known that we, Leslie B. Haigh and Franklin A. Stearn, a subject of Great Britain and a citizen of the United States, and residents of West Orange and Westfield, in the counties of Essex and Union, respectively, and both State of New Jersey, United States of America, have invented a new, original, and ornamental Design for Telephone Jack Bracket, of which the following is a specification, reference being had to

the accompanying drawing, forming part thereof.

Figure 1 is a perspective view of the telephone jack bracket, showing our new design, and

Figure 2 is a side view of the telephone jack bracket shown in Figure 1.

We claim:

The ornamental design for a telephone jack bracket, as shown.
